(57) **CLAIM**

The ornamental design for a containment pouch for a pet
leash, as shown and described.

DESCRIPTION

FIG. 1 is a perspective view of a containment pouch for a pet
leash showing the new design;

FIG. 2 is a back view thereof;

FIG. 3 is a front view thereof;

FIG. 4 is a left side view thereof;

FIG. 5 is a right side view thereof showing the side opposite
that shown in FIG. 4;

FIG. 6 is a top view thereof;

FIG. 7 is a bottom view thereof; and,

FIG. 8 is a perspective view thereof showing the contain-
ment pouch for a pet leash in a state of use.

The broken lines in the drawings depict environmental
subject matter that forms no part of the claimed design.

1 Claim, 7 Drawing Sheets
